UNITED STATES PATENT OFFICE.

MATTHEW HENDERSON, OF TORONTO, ONTARIO, CANADA, ASSIGNEE TO THE JAMES MORRISON BRASS MANUFACTURING COMPANY, LIMITED, OF TORONTO, ONTARIO, CANADA, A CORPORATION OF CANADA.

WATER-JET LIFTER.

1,102,505.

Specification of Letters Patent. Patented July 7, 1914.

Application filed January 6, 1913. Serial No. 740,474.

To all whom it may concern:

Be it known that I, MATTHEW HENDERSON, of the city of Toronto, in the county of York, in the Province of Ontario, Canada, have invented certain new and useful Improvements in Water-Jet Lifters, of which the following is the specification.

My invention relates to improvements in water jet lifters and the object of the invention is to devise a device of this class which will have a maximum lifting power and the parts of which may be readily separated apart for the purpose of cleaning or repair and it consists essentially of a main tubular body having an inlet at its upper end, an outlet at its lower end, and a peripheral suction inlet in proximity to the upper end of the body, a nozzle secured and extending into the inlet end of the casing, a suction tube vertically opposite the nozzle, and secured within the casing intermediately of its length and a vacuum cup secured to the outer end of the casing in to which the suction tube leads as hereinafter more particularly explained by the following specification.

Figure 1, is an elevation of my device. Fig. 2, is a vertical section through Fig. 1 taken at right angles thereto. Fig. 3, is a plan section on line $x-y$ Fig. 1. Fig. 4, is an enlarged perspective detail of the vacuum cup.

In the drawings like letters of reference indicate corresponding parts in each figure.

A is the body of the lifter provided with an internally threaded inlet orifice A' at its upper end and an outlet orifice A'' at its lower end, and an intermediate reduced internally threaded portion A^* having an inner threaded portion A^* forming a shoulder A^* .

A^* is a suction inlet leading into the body of the lifter in proximity to its upper end.

A' is the suction chamber into which the suction inlet A^* leads.

B is a nozzle threaded into the internally threaded inlet orifice A' and provided with an internally threaded enlargement B' shoulderng down on the top of the lifter body around the opening A' and designed to be connected to a suitable water conduit.

C is a suction tube threaded into the reduced portion A^* of the lifter body. The suction tube C is provided with an enlarge-

ment C' bearing against the shoulder A^* of the lifter body. The suction tube C is in vertical alinement with the nozzle B, the internal diameter of which is enlarged at its upper end.

D is a vacuum cup comprising an outer wall D' having an outlet orifice D² at its lower end around which extends an annular threaded boss D³ for connecting it to a suitable discharge pipe.

D⁴ is the vacuum cup proper which is supported within the outer portion D' by the connecting spider D⁵. The upper end of the portion D' is provided with an annular flange D⁶ having a beveled upper face D⁷ fitting against the internally beveled face 70 A⁸ formed around the outlet end of the lifter body A.

E is a securing nut designed to extend around the portion D' and to bear against the lower face of the shoulder D⁸ and to be threaded on to the lower end of the lifter body to hold the beveled upper end of the portion D' against the beveled end A⁸ of the body A.

It will be noticed that the suction tube C extends partially into the vacuum cup D⁴. In operation a suitable pipe is connected with the suction inlet and the free end of such pipe is immersed in water contained in a cellar or other location from which it is desired to lift the water. Water is then fed through the jet B from a suitable conduit, the jet of water passing down through the suction tube C into the cup D⁴, such water foaming up and passing over the upper edge of the cup and down between the cup D⁴ and the portion D' to the outlet D². By this means the air is gradually drawn from the suction chamber A' and the suction inlet A⁸ into the cup D⁴ and is then contained in water foam carried over the edge of the cup to the outlet D². By this means a vacuum is formed in the chamber A' which is effectually sealed by the water contained in and passing through the cup D⁴. By this means the water is lifted from the cellar to the suction inlet A⁸ and is carried down through the lifter by the jet of water fed from the nozzle B.

I am aware that there have been other vacuum suction lifting devices but these have been so constructed as to only have a very limited lifting power. With my de-

vice I am enabled to draw water from a location at a considerable distance away from the lifter.

What I claim as my invention is.

- 5 1. A water jet lifter comprising a tubular body having an inlet orifice at one end and an outlet orifice at the opposite end, and a suction inlet leading into the side thereof, a water jet nozzle extending through the 10 inlet orifice, a suction tube secured within the body in vertical alinement with the nozzle, and a vacuum cup secured to the casing in vertical alinement with the nozzle and suction tube, as and for the purpose specified.
- 15 2. A water jet lifter comprising a tubular body having an inlet orifice at one end, and an outlet orifice at the opposite end, and a peripheral orifice located in proximity to the upper end thereof, a water jet nozzle secured in the inlet orifice of the body, a suction tube located intermediately of the 20 length of the lifter body in alinement with the nozzle, and a vacuum cup connected to the outlet end of the body and comprising an outer cup portion having an outlet orifice at its lower end, and an inner cup portion supported in the outer cup portion and spaced apart from the walls thereof and in 25 to which the suction tube extends, as and for the purpose specified.
- 30 3. A water jet lifter comprising a tubular body having an inlet orifice at its upper

end, an outlet orifice at its lower end and an internally threaded reduced intermediate 35 portion, a suction tube threaded in to such intermediate portion, a nozzle secured to the inlet orifice in alinement with the suction tube and a vacuum cup removably secured against the outlet orifice of the body and 40 comprising an outer tubular cup portion having an outlet orifice at its lower end, and an inner tubular cup portion supported within the outer cup portion and spaced apart from the walls thereof, as and for the 45 purpose specified.

4. In a water jet lifter, a nozzle and a vacuum cup arranged in longitudinal alinement with the nozzle, as and for the purpose 50 specified.

5. In a water jet lifter, a nozzle and a vacuum cup comprising an outer member having an exit at the bottom, and an inner member supported in the outer member and having the walls thereof spaced apart from the walls of the outer member, as and for 55 the purpose specified.

6. In a water jet lifter, a nozzle, a suction tube, and a vacuum cup arranged in longitudinal alinement, as and for the purpose specified.

MATTHEW HENDERSON.
